BUFFING AND POLISHING MACHINE

Carl O. Johnson, Springville, N. Y., assignor to
Ralph B. Waite, Springville, N. Y.

Application September 30, 1937, Serial No. 166,691

5 Claims. (Cl. 51—85)

This invention relates to certain new and useful improvements in buffing or polishing machines, and has particular reference to the type of machine disclosed in the application for patent filed by Carl O. Johnson for Buffing or polishing machines on May 27, 1936, Serial Number 82,103 and embodies improvements in the art thereover.

In the buffing and polishing machine disclosed in the application of Carl O. Johnson, a frame structure supports a pair of cooperating slides, one of the slides being mounted on the frame structure to reciprocate through the medium of guides in directions at right angles to the longitudinal axes of buffing or polishing rolls while the other slide is directly mounted upon the first named slide to reciprocate in a direct line parallel to the longitudinal axes of the rolls.

An object of the present invention is to change the direction of movement of the second slide with reference to the first slide, the latter being mounted for reciprocatory movements in directions at right angles to the longitudinal axes of the buffing or polishing rolls while the second slide is resiliently supported relative to the first slide and is caused to move in oscillatory swinging arcuate paths relative to the first named slide for presenting the articles to be buffed or polished to the buffing or polishing rolls in a manner different from the disclosure in the aforesaid Johnson application and with the idea of improving the buffing or polishing operation.

With the above and other objects in view that will become apparent as the nature of the invention is better understood, the same consists in the novel form, combination and arrangement of parts hereinafter more fully described, shown in the accompanying drawings and claimed.

In the drawings:

Figure 1 is a top plan view of the buffing or polishing machine constructed in accordance with the present invention;

Figure 2 is a front elevational view showing the upper and lower polishing rolls, the separate motor drive for each roll and the devices for operating the slides and swinging holder;

Figure 3 is a fragmentary top plan view showing the reciprocating slide that moves toward and away from the polishing rolls and the resilient arms attached to the slide with the work holder carried by the free swinging ends of the resilient arm, together with the devices for swinging the arms against resiliency thereof;

Figure 4 is a fragmentary side elevational view,

partly broken away of the mechanism shown in Figure 3; and

Figure 5 is a detail sectional view taken on line 5—5 of Figure 3, showing the gear drive and eccentric disk for imparting swinging movement to the resilient arms that carry the holder.

The machine as shown in Figs. 1 and 2 of the drawings is comparable with the disclosure in the application of Carl O. Johnson hereinbefore mentioned and in general comprises a table 10 supported on standards 11 and from which table 10 an upright bearing 12 rises from each end.

As shown in Fig. 1, a rock shaft 13 is journaled in the upper ends of the uprights 12 and said rock shaft carries a pair of rock arms 14 shown in Fig. 15 that rotatably support at their free ends a polishing roller 15, the shaft 16 of the roller 15 being a part of or connected to the shaft of the electric motor 17. A pair of rock arms 18 are supported on a rock shaft 19 in the upright 12 below the 20 rocker shaft 13 and rotatably support at their free ends the polishing roller 20, the shaft 21 of which forms a part of or is connected to the shaft of the electric motor 22. The arms 14 and 18 at their points of connection with the rock shafts 16 and 19 are geared together as at 23 to cause simultaneous movement of the polishing rolls 15 and 20 toward and away from each other when the same are adjusted by means of the adjusting screw 24 threading through blocks carried 30 by the free ends of a pair of arms 14 and 18 at one end of the machine opposite the geared connections 23 between the arms at the opposite end of the machine.

As shown more clearly in Fig. 2, a pair of guide rails 25 is carried by the upper side of the table top 10 and extend in direction at right angles to the longitudinal axes of the polishing rollers 15 and 20. A slide plate 26 has the opposite side edges 27 slidably and interlockingly engaged with 40 the guides 25 and is movable over said guides in a direction at right angles to the longitudinal axes of the polishing rollers 15 and 20.

The devices for effecting reciprocatory movements of the slide plate 26 include in general a 45 fluid cylinder 28 secured to and depending from the table top 10 with a piston 29 projecting from one end of the cylinder 28 engaged with an arm 30 at a point forwardly of the front edge of the table top 10 with the arm 30 extending upwardly for 50 attachment to the underside of the slide plate 26. The devices for effecting reciprocation of the piston rod 29 within the fluid cylinder 28 broadly include a pump 31 shown in Figure 1 as having a belt and pulley connection 32 with the shaft 21 55

of the electric motor 22, the pump 31 drawing fluid from the tank 33 in a standard 11 by way of the pipe 34 and feeding the fluid under pressure by way of the pipe 35 to a multi-way valve 36. Pipes 37 from the multi-way valve 36 deliver the fluid to the fluid cylinder 28 to effect reciprocation of the piston 29 and reciprocatory movements of the slide plate 26, the fluid in the cylinder 28 bleeding through the pipe lines 37 through the multi-way valve 36 and being returned by way of the pipe 38 to the fluid tank 33. If desired, the fluid flowing through the pipe 35 from the pump 31 may be returned or by-passed to the tank 33 before delivery to the multi-way valve 36 by way of the valve device 39 controlled by the operating lever 40 as shown in Figs. 1 and 2.

The stem 41 of the multi-way valve 36 shown in Fig. 2 as rising from said valve 36 has devices associated therewith that are operated by movements of the slide plate 26 for the automatic operation of the multi-way valve to effect reciprocations of the piston 29 in the fluid cylinder 28 and as shown in Fig. 1, a rod 42 is mounted in bearings 43 and 44 projecting from one side edge of the slide plate 26, the rod 42 being threaded as at 45 for threading through the bearing block 44 and adjusted by means of the operating handle 46. An arm 47 has one end thereof fixed to the upper end of the stem 41 of the multi-way valve 36 and the free end of the arm 47 has a pin and slot connection 48 with a second arm or lever 49 that is pivotally supported as at 50 to the adjacent side of a slide plate 26. A pair of stop blocks 51, one of which is shown in Fig. 1, is adjustably attached to the rod 42 by means of a pin 52 for anchoring the stop block 51 in selected openings 53 in said rod and during reciprocatory movement of the slide plate 26, the stop or abutment blocks 51 engage the lever 49 to move the same on its pivotal mounting 50 and also shift the arm 42 for reversing the position of the multi-way valve 36. Means is provided for holding the multi-way valve in its adjusted position for the feeding of fluid to either end of the fluid cylinder 28 and includes a coil spring 54 having one end attached to the pin and slot connection 48 between the arms 47 and 49 while the other end of the spring is anchored as at 55 to the slide plate 26, the spring being of the coiled type and tensioned intermediate its ends thereof by being stretched and selectively engaged with notches 56 in an angle plate 57 rising from the slide plate 26. The structure described in connection with the reciprocation of the slide plate 26 is substantially identical with the showing in the aforementioned Johnson application.

A resiliently mounted work holder that causes the work holder to swing in an oscillatory arcuate path is carried by the reciprocating slide plate 26 and as shown in Fig. 1, the rear end of the slide plate 26 carries integral laterally projecting plate portions 58 to which a pair of resilient blade-like arms 59 and 60 are attached at their rear ends and are substantially co-extensive with the length of the slide plate 26. In lieu of the plate extension 58 on the slide plate 26, it is also intended to provide a pair of rigid bracket arms 58a as shown in Fig. 3 for attaching the resilient side arms 59 and 60 to the rear end of the slide plate 26. In each instance, the resilient blade-like arms 59 and 60 are anchored at their rear ends with the forward or other ends of the resilient arms freely disposed for attachment to upright work holders 61, the forward ends of the

resilient side arms 59 and 60 being connected together by a cross-rod 62 and a tie rod 63. Clamp devices 64 as shown in Figures 1 and 3 are carried by the upright work holders and include bars 71 having pin supports for knife blades 78 or other articles to be polished or buffed.

The devices for effecting oscillatory swinging movements of the free ends of the resilient side arms 59 and 60 and the upright work support 61 include a worm shaft 65 shown in Fig. 2 as 10 having a belt and pulley connection 66 with the shaft of the electric motor 17, the worm shaft 65 having a suitable bearing in a standard 11, table top 10 or other support and said worm shaft 65 as shown in Fig. 5 has a worm 67 that meshes 15 with the worm wheel 68 secured to the lower end of a shaft 69 that is journalled in a bearing 70 extending above the table top 10. The upper end of the shaft 69 carries an eccentrically disposed end projecting pin 71 upon which a roller bearing 72 is freely rotatable, and said roller bearing 72 is disposed for contact or engagement with the inner side of the resilient side arm 59 as shown in Figs. 2 to 4. To maintain constant engagement between the roller bearing 72 and the resilient side arm 59, a collar 73 is fixed to the tie rod 63 intermediate its ends and in spaced relation to a housing 74 through which the tie rod 63 freely extends, an expansion spring 75 being positioned between the collar 73 and housing 74 for normally influencing the tie rod 63 in a direction for holding the resilient side arm 59 engaged with the roller bearing 72.

From the above detailed description of the invention, it is believed that the construction and operation thereof will at once be apparent, it being noted that the fluid means effects reciprocation of the slide plate 26, the motors 17 and 22 rotating the polishing or buffing rollers 15 and 20 while rotation of the roller bearing 72 effects a substantial pivotal movement of the side arms 59 and 60 on their points of attachment to the slide plate 26 with the free ends of the resilient side arms 59 and 60 that carry the work holder moving through oscillatory swinging arcs of movement, the articles held by the work holder being moved toward and away from the buffing rollers and into and out of the bight between the rollers, the articles being buffed moving in orbital paths with the result that excess buffing or polishing will not be concentrated at any particular point so that the article to be buffed will be similarly treated over the entire area thereof. A distinctive feature of the invention includes the reciprocating slide plate 26 with the resilient 55 blade-like arms anchored at one end to the rear end of the slide plate with the free ends of the arms that carry the work holder swinging in oscillatory arcuate paths.

I claim:

1. In a polishing and buffing machine, a pair of buffing and polishing rolls, means to drive the rolls, a slide member movable towards and away from the rolls in a line at right angles to the longitudinal axes of the rolls, a pair of resilient arms anchored at one end to the slide member, a work holder carried by the other end of the resilient arms and means for moving the arms against resiliency thereof to cause the work holder to oscillate through arcuate paths, traversing the path of movement of the slide member.

2. In a polishing and buffing machine, a pair of buffing and polishing rolls, means to drive the rolls, a slide member movable towards and away from the rolls in a line at right angles 75

to the longitudinal axes of the rolls, a pair of resilient arms anchored at one end to the slide member, a work holder carried by the other ends of the resilient arms and a cam element engageable with one of the arms for moving the arms against resiliency thereof to cause the work holder to oscillate through arcuate paths traversing the path of movement of the slide member.

5. In a polishing and buffing machine, a pair of buffing and polishing rolls, means to drive the rolls, a slide member movable towards and away from the rolls in a line at right angles to the longitudinal axes of the rolls, a pair of resilient arms anchored at one end to the slide member, a work holder carried by the other ends of the resilient arms and a cam element engageable with one of the arms for moving the arms against resiliency thereof to cause the work holder to oscillate through arcuate paths traversing the path of movement of the slide member, and means for maintaining the engagement between the cam element and associated resilient arm.

3. In a polishing and buffing machine, a pair of buffing and polishing rolls, means to drive the rolls, a slide member movable towards and away from the rolls in a line at right angles to

the longitudinal axes of the rolls, a pair of resilient arms anchored at one end to the slide member, a work holder carried by the other ends of the resilient arms and a cam element engageable with one of the arms for moving the arms against resiliency thereof to cause the work holder to oscillate through arcuate paths traversing the path of movement of the slide member, and operative connections between the driving means for a roll and said cam element.

5. In a polishing and buffing machine, a pair of buffing and polishing rolls, means to drive the rolls, a slide member movable towards and away from the rolls in a line at right angles to the longitudinal axes of the rolls, a pair of resilient arms anchored at one end to the slide member, a work holder carried by the other ends of the resilient arms and a cam element engageable with one of the arms for moving the arms against resiliency thereof to cause the work holder to oscillate through arcuate paths traversing the path of movement of the slide member, and means for maintaining the engagement between the cam element and associated resilient arm, and operative connections between the driving means for a roll and said cam element.

C. O. JOHNSON.
